UNITED STATES PATENT OFFICE.

ALBERT P. LEE, OF CHICAGO, ILLINOIS, ASSIGNOR TO LEE LOADER & BODY CO., OF CHICAGO, ILLINOIS.

DUMPING-HOPPER.

1,325,495.

Specification of Letters Patent.

Patented Dec. 16, 1919.

Application filed January 15, 1917. Serial No. 142,419.

To all whom it may concern:

Be it known that I, ALBERT P. LEE, a citizen of the United States, residing at Chicago, in the county of Cook and State of Illinois, have invented a certain new and useful Improvement in Dumping-Hoppers, of which the following is a full, clear, concise, and exact description, reference being had to the accompanying drawings, forming 10 a part of this specification.

My invention relates to dumping hoppers and has for its object the provision of an improved form of construction for a rolling hopper of this type in which in the preferred form a runway for the hopper is used having such a configuration or design that the natural body form of the hopper need not be modified, the rail permitting the rolling of the hopper from a central charge 15 carrying to a limiting discharge position with an even movement. The runway which I prefer to use may be in the form of a rail and its active face consists of what I might call a broken back curve. 20 In using the term broken back curve, I do not mean to limit myself to a rail having its operative face made up of various curves, as these segments or sections may be straight lines, but I am using the word curve in the 25 sense that it is used in connection with platted diagrams using coördinates. In describing curves of that nature, these curves are frequently found to be straight lines, and it is in that sense that I use the term, 30 as the essence of the invention is not dependent upon having the various rail sections of a curved outline, although in the preferred form certain parts of the rail seem to be better adapted to perform their 35 functions if the outline is curved.

My invention further contemplates the use of universally mounted outrigger holding devices.

In the description herein and in the drawings I show a dumping hopper adapted to roll to both sides of a central charge carrying position, but it is of course apparent that the invention naturally contemplates a structure in which the hopper would roll 45 only to one side of its central charge carrying position.

I will describe this particular form which my invention may take by referring to the accompanying drawing, in which—

50 Figure 1 is an end view of a vehicle hav-

ing my improved hopper mounted in position;

Fig. 2 is a transverse sectional view of the hopper and rail; and

Fig. 3 is a detail view showing the universal mounting of the outrigger structure.

The structure as illustrated constitutes a vehicle having the wheels 1, 1, surmounted by a framework 2, which framework carries a runway 3. This runway is of the broken back type, the reasons for which will presently appear. The runway here shown is in the form of a rail. A dumping hopper 4 shown in its central position in Fig. 1 and in one of its limiting dumping positions in dotted lines in Fig. 1 is adapted to roll upon said runway to either side of its central position. When the hopper is in its central position, suitable supporting devices 5, 5, presently to be explained assist in retaining the hopper in its central position. There is furthermore provided a bolt 6 carried by a framework 7 which enters a recess 8 to assist in holding the hopper in its central position. Suitable limit chains 9 prevent the hopper from leaving the rail when in its limiting position.

The framework 7 is carried by the framework 2. The holding devices 5 have an arm 10 to which is pivotally mounted a second arm 11, which arm at its upper extremity has a cam surface engaging a corresponding surface and the sides of the hopper, thus to lock the hopper in its central position. The arm 10 is pivotally mounted on a lug 12 by the bolt 13 and this lug 12 is pivotally mounted upon the rail 3 by the bolt 14. A projecting arm 15 at the lower extremity of the arm 10 prevents the arm 10 from moving inwardly too far. It will be seen by reason of this universal mounting of the arm 10 that it can be swung so that it hangs below the rail, thus to prevent obstructing the hopper as it moves toward its limiting position and furthermore, that this arm 10 may swing transversely of the swinging movement of the lug 12, thus to amply clear the wheels 1 when it is desired to permit the dumping of the hopper.

The constructional features relating to the hopper and its runway are more clearly apparent from Fig. 2. The hopper consists of the bottom portion 16, the inclined sides 17, 17, and the mouth portion 18. The portions 16 and 17 are preferably provided with

22

lugs or rivets 19 which are adapted to enter holes 20 provided in the rail 3 so as to maintain an accurate register between the hopper and its coöperating rail. The hopper is provided with pivot pins 21 which when the hopper is in its limiting position to either side coöperate with the hooked extremities 22 of the rail, thus to permit actual pivoting of this hopper about said pins to secure a complete discharge of the contents. The limit chains 9 coöperate at this time to prevent the hopper from moving farther than the position shown by dotted lines in Fig. 1. The runway or rail 3 has a central portion having the oppositely inclined sections 23, 23. These sections may continue their inclination so that they form an apex at the center, or may have a slightly flattened portion as indicated in the drawing. The flattened portion however should be small so that when the hopper is given a slight push it will promptly roll down either inclined portion 23. These inclined portions extend a certain distance conforming to the developed length of the bottom portion 16 of the hopper. The rail 3 then has curved sections 24, 24 which coöperate with the inclined side sections 17 of the hopper. The curved sections 24 may preferably have the same radius as the radius of the bottom portion 16, in which event the hopper continues its rolling action the same as though the rounded bottom portion 16 were extended right up to the pivotal point 21. A much greater simplicity of construction of the hopper is thus apparent in that the natural outline of the hopper is accommodated upon a rail in such manner that the hopper has a smooth even rolling motion from its central position to its limiting positions. It must further be pointed out that if the inclined portion 23 were extended downwardly in place of the rounded sections 24, under which conditions, of course, the rounded bottom 16 of the hopper would have to be continued along to the pivotal point 21, that then these extensions of the sections 23 would as a general rule seriously interfere with the position of the wheels 1. According to my improved construction the rails are thus curved to carry them a safe distance over the wheels 1. This curving action may be carried out to any desired extent to avoid the said wheels or any other obstructing parts of the vehicle.

It is of course readily apparent that the inclined sections 23 of the rail and the inclined sections 17 of the hopper need not necessarily be straight lines. Their outline, however, must be such as to conform with the coöperating outline of the rail. Similarly any other portions may be given a curvature of different radius, or may consist of portions of straight lines. The essential feature is that the rail is of such a

nature that it accommodates substantially what should be the natural outline of the hopper so far as this preferred embodiment is concerned.

When using the word "apex" in the claims, I mean that word to be understood as the meeting point; for instance, between such portions as the portions 23 and 24, there being a change in direction of the rail at such a point. While the word "apex" might ordinarily be understood to be a point, yet it is readily apparent that the meeting point of the sections 23 and 24 may be slightly rounded as is customary in the manufacture of all devices. I mean the word apex in the claims broadly to of course include such rounding, if that is done.

From what has been described it is thought the nature of my invention will be readily clear to those skilled in the art. Having however thus described one form which my invention may take, what I claim as new and desire to secure by Letters Patent is:

1. A device of the character described comprising a runway and a rolling hopper adapted to roll on said runway from a central charge carrying to a limiting dumping position, said runway having a slightly flattened central portion and an active face forming a broken back curve the initial section whereof near the central portion having a straight line surface with a downward inclination toward its extremity, and succeeding curved sections thereof having a less inclination than said initial portion.

2. A device of the character described comprising a runway and a rolling hopper adapted to roll on said runway from a central charge carrying to a limiting dumping position, said runway having a slightly flattened central portion and an active face forming a broken back curve the initial section whereof near the central portion having a straight line surface with a downward inclination toward its extremity, succeeding sections thereof having a less inclination than said initial section, and said hopper having a rounded bottom portion to coöperate with said initial section and an abruptly inclined side wall to coöperate with said succeeding sections.

3. A device of the character described comprising a runway and a rolling hopper adapted to roll substantially automatically on said runway from a central charge carrying to a limiting dumping position, said runway having an active face forming a broken back curve one section whereof having a substantially straight line surface with a downward inclination toward its extremity, and succeeding sections thereof having a less inclination than said one section in order to clear the wheels of the vehicle on which the runway is mounted.

4. A device of the character described comprising a runway and a rolling hopper adapted to roll substantially automatically on said runway from a central charge carrying to a limiting dumping position, said runway having an active face forming a broken back curve one section whereof having a downward inclination toward its extremity, succeeding sections thereof being upwardly convexed and having a less inclination than said one section, in order to clear the wheels of the vehicle on which the runway is mounted, and said hopper having a bottom portion to coöperate with said one section and an abruptly inclined side wall to coöperate with said succeeding section. 60
5. A device of the character described comprising a runway and a rolling hopper adapted to roll substantially automatically on said runway from a central charge carrying to limiting dumping positions on either side of said central position, said runway having an active face forming a broken back curve, certain sections whereof being flat and having a downward inclination toward their corresponding extremities, and succeeding sections thereof being curved above the planes of the first sections and having a less inclination than said certain sections in order to clear the wheels of the vehicle on which the runway is mounted. 65
6. A device of the character described comprising a runway and a rolling hopper adapted to roll substantially automatically on said runway from a central charge carrying to limiting dumping positions on either side of said central position, said runway having an active face forming a broken back curve, certain sections whereof at opposite sides of its central portion having a downward inclination toward their corresponding extremities, and succeeding sections thereof projecting above the planes of said first sections and having a less inclination than said certain sections and said hopper having a rounded bottom portion to coöperate with said certain sections, and abruptly inclined side walls to coöperate with said succeeding sections, there being an abrupt change in direction between the surfaces of said certain sections and said succeeding sections. 70
7. A device of the character described comprising a runway and a rolling hopper adapted to roll substantially automatically on said runway from a central charge carrying to limiting dumping positions on either side of said central position, said runway being adapted to clear the wheels of the vehicle on which it is mounted having an active face forming a broken back curve consisting of a central portion, sections at opposite sides of the central portion having flat surfaces with downward inclination toward their corresponding extremities, and succeeding upwardly convexed sections thereof having a less inclination than said first sections and lower than said central portion, the distance from tip to tip of said runway being substantially equal to the greatest width of said hopper. 75
8. In a device of the character described a rolling hopper having curved and straight portions, and a complementary runway having straight and curved sections which coöperate respectively with the curved and straight portions of the hopper to cause automatic and smooth rolling of the hopper to its dumping position, the curved section of the runway being upwardly convexed 80 and extending above the plane of the straight section. 85
9. A runway for a flared rolling hopper comprising a central portion, downwardly inclined straight sections at opposite sides of the central portion and upwardly convexed sections at the ends of the straight sections, each curved section forming an apex with the adjoining end of the respective straight sections. 90
10. In a device of the character described a rolling hopper having curved and straight portions, and a complementary runway having straight and curved sections which coöperate respectively with the curved and straight portions of the hopper to cause automatic and smooth rolling of the hopper to its dumping position, the curved sections of the runway being upwardly convexed and extending above the planes of the straight sections. 95
11. A runway for a complementarily formed rolling hopper comprising a downwardly inclined substantially straight section and an upwardly convexed curved section beyond said straight section, the curved section of the runway extending above the plane of the straight section. 100
- In witness whereof I hereunto subscribe my name this 10th day of January, A. D. 110 1917.
